ELECTRIC FURNACE.

1,386,155.

Specification of Letters Patent.

Patented Aug. 2, 1921.

Application filed July 31, 1919. Serial No. 314,409.

To all whom it may concern:

Be it known that we, WALTER S. BURCH and WILLIAM A. SCHELL, citizens of the United States, residing at Rochester, in the county of Monroe and State of New York, have invented certain new and useful Improvements in Electric Furnaces; and we do hereby declare the following to be a full, clear, and exact description of the invention, such as will enable others skilled in the art to which it appertains to make and use the same.

This invention relates to electric furnaces for the performance of chemical reactions at high temperatures. The invention is particularly applicable to the manufacture of calcium carbid, although it may be used for various other reactions involving similar conditions.

One object of the invention is to produce a furnace which will operate on the continuous-discharge principle, while avoiding the difficulties which have been encountered in previous attempts to secure this result. To this end the furnace of the present invention is provided with electrodes of such form and arrangement that it is impossible for any unconverted solid particles to reach the discharge-passage of the furnace without passing through the sphere of operation of the electrodes. By the same form and arrangement of parts the necessity of using refractory, non-conductive material in close proximity to the region of maximum temperature is avoided.

In previous attempts to produce continuous-discharge furnaces it has been proposed to permit the raw material to descend through a tube or reaction-chamber in which arcs are produced between electrodes projecting laterally into the chamber, the escape of the material being unrestricted. In such a construction, however, at least where used with refractory materials such, for example, as calcium-carbid, particles of uncombined material are sure to escape the action of the arcs and to be discharged with the combined material.

On the other hand, it has been proposed to use an arrangement in which one electrode forms the bottom of the reaction-chamber and is perforated to provide an outlet, while the other electrode depends into close proximity with the bottom elec-

trode and is concentric with the discharge-opening. In this arrangement the electrodes can be adjusted into such close proximity as to insure that every particle of material shall be subjected to the action of the current before its escape. This arrangement has the disadvantage, however, that the current between the electrodes is effective only upon material in close proximity to the discharge-opening, and since this opening is necessarily smaller in diameter than the reaction-chamber, the unmelted raw-material will not feed steadily to the electrodes but tends to arch and come to rest.

The present inventors have discovered that by a suitable arrangement of electrodes it is possible to produce a furnace possessing the advantages, and avoiding the defects, of both of the arrangements just described. This is accomplished by using two or more primary electrodes, which melt the bulk of the material and insure its continuous descent in the reaction-chamber, together with two or more refining electrodes which are so arranged that no particles of uncombined material can pass them. By the use of these two sets of electrodes in combination a furnace is produced which will act continuously and discharge a refined product free from unconverted raw-material.

Other objects of the invention, and the features of construction by which they are attained, will be apparent from the following description of the illustrated embodiment of the invention.

In the accompanying drawings Figure 1 is a vertical median section of a furnace embodying the invention. Fig. 2 is a vertical section on the line 2—2 in Fig. 1. Fig. 3 is a detail plan-view of the bottom members of the furnace. Figs. 4 and 5 are a vertical section and a plan-view of the bottom-members in a modified form. Figs. 6 and 7 are diagrams showing two methods of energizing the electrodes of the furnace.

The invention is illustrated as embodied in a furnace having a body 10 of suitable refractory non-conductive material, which forms the wall of a reaction-chamber 11. The bottom of the reaction-chamber, in the embodiment shown in Figs. 1, 2 and 3, is formed by two blocks 12 of graphite or carbon, together with two electrode-members 13, which are in contact at their inner ex-

tremities. These extremities are recessed, so as to provide, when in their normal engagement, a circular orifice 14 through which molten material is discharged from the furnace.

The members 13 also constitute, together, one of the electrodes of the furnace; and since they are in contact with the conductive blocks 12 the latter also contribute to their action and may be considered as a part of the same electrode, although this is not essential to the operation of the furnace.

In place of the two blocks 12 a single block or slab 18 of graphite or carbon may be used, as shown in Figs. 4 and 5, this slab being provided with a central opening 19 and with a transverse channel at the bottom in which the members 13 are seated.

Coöperating with the bottom electrode is an electrode 15 in the form of a graphite or carbon cylinder, which depends into the reaction-chamber directly in line with the discharge-orifice 14. This central electrode moves vertically in a refractory guide-tube 16 at the top of the furnace, and the vertical position of the holder and the electrode are controlled by suitable means such as a hoisting-tackle 17.

The discharge-orifice has a downwardly tapering form, as shown in the drawings, and the lower end of the central electrode 15 is pointed at a similar angle, so that when the central electrode is lowered toward the bottom electrode it acts as a needle-valve, by which the discharge-orifice may be controlled or entirely closed.

The electrodes 13 and 15 are connected, respectively, with the terminals of a source of current, so as to produce a current-flow, in a substantially vertical direction, through material in the bottom of the reaction chamber. When the central electrode is adjusted close to but out of contact with, the bottom electrode all material escaping through the orifice 14 must first pass between the surface of the bottom electrode and the adjacent surface of the central electrode. Particles of solid unconverted material are thus prevented from falling directly through the outlet with the liquefied material, and are compelled to pass first through a narrow space where they are subjected to a highly concentrated heating effect, whereby they are fully converted and liquefied. The space between the electrodes may be made, by means of the tackle 17, as narrow as may be necessary according to the nature and purity of the materials and the quality of the product required.

In accordance with the broader aspects of the invention the perforated bottom electrode need not necessarily have the composite construction shown and described, but this construction affords convenient provision for maintaining the correct form of the

outlet orifice, for upon withdrawal of the members 13 their ends may be dressed as may be required, to compensate for wear.

While the bottom electrode and the central electrode perform the final refining and liquefying operation on the material, the furnace is provided with two or more primary electrodes 20, which enter the reaction-chamber laterally, and which are movable for the purpose of adjustment. These electrodes are spaced farther apart than the refining electrodes, while they project sufficiently beyond the firebrick walls to relieve the walls from the destructive temperature of reaction. These electrodes 20 constitute, in the illustrated furnace, the main working members and are supplied with the greater part of the energy consumed in the furnace.

The several electrodes of the furnace may be energized in various ways, and the current between the primary electrodes and that between the refining electrodes are preferably under independent control. As shown in Fig. 4, the two sets of electrodes 90 may be energized from two phases of a single polyphase system, or, as shown in Fig. 5 one set of electrodes may receive alternating current while the other is fed with direct current. The number of primary electrodes used is also variable, although two have been found to give satisfactory results.

The usual mode of operation of the furnace is as follows:

The central electrode 15 is lowered into engagement with the bottom electrode, so as to close the outlet-orifice against the premature escape of material. A charge of raw material is then introduced, and the current is applied to the primary electrodes, thus heating and partly converting the material. The central electrode may then be energized and slightly lifted, thus permitting the material to escape as fast as it is refined and liquefied. With the normal operation thus established the central electrode is adjusted to the height at which the greatest production occurs without the escape of unconverted particles. The reaction-chamber is kept full by the addition of raw material as fast as it is consumed. The finished material is discharged into a pit 21 beneath the furnace, and the furnace is provided with peek-holes 22 normally closed by stoppers 23, through which the operation may be observed. The raw material is introduced through openings 24, which are normally closed by doors 25, and flues 26, at the top of the furnace, discharge the fumes and gases resulting from the reactions in the 125 furnace.

When it is desired to interrupt the operation of the furnace the current between all the electrodes is continued until the raw material remaining in the furnace is consumed,

and the energization of the electrodes 13, 15 is not interrupted until the material around the central electrode and adjacent the discharge-opening has liquefied and escaped, 5 leaving the central electrode free to be moved up and down.

The invention is not limited to the embodiment thereof hereinbefore described and illustrated in the accompanying drawings, but it may be embodied in various other forms within the nature of the invention and the scope of the following claims.

The invention claimed is:

1. An electric furnace comprising: a refractory body provided with a reaction-chamber; an electrode, at the bottom of the chamber, comprising a plurality of retractable members normally in engagement and provided with recesses in their contiguous extremities constituting a discharge-opening; and a second electrode coöperating with the first.

2. An electric furnace comprising: a refractory body provided with a reaction-chamber; members of carbonaceous material, at the bottom of the chamber, including a perforated plate and a plurality of removable electrode-members meeting at the perforation in said plate and having a discharge-opening formed between their contiguous extremities; and an electrode coöperating with said electrode-members.

3. An electric furnace comprising: a refractory body provided with a reaction-chamber; primary electrodes operable upon material in said chamber; refining electrodes located below the primary electrodes and acting upon the material after its descent from the sphere of action of the primary electrodes, and means for regulating the escape of the refined material.

4. An electric furnace comprising: a refractory body provided with a reaction-chamber; primary electrodes in said chamber; a source of current for the primary electrodes; refining electrodes located below the primary electrodes and acting upon the material after its descent from the sphere of action of the primary electrodes, one of 50 the refining electrodes being adjustable toward and from the other; and an independent source of current for the refining electrodes.

5. An electric furnace comprising: a refractory body provided with a reaction-chamber; primary electrodes operable within said chamber; and refining electrodes lo-

cated below the primary electrodes and closer together than the latter.

6. An electric furnace comprising: a refractory body provided with a reaction-chamber; primary electrodes operable within said chamber; and refining electrodes, between which the molten material escapes from the chamber, located below, and nearer together than the primary electrodes.

7. An electric furnace comprising: a refractory body provided with a reaction-chamber having an outlet at the bottom; electrodes arranged to pass a current horizontally through the upper part of a body of material in said chamber; and independently operating electrodes arranged to pass current vertically through the lower part of said material adjacent to the outlet from the chamber.

8. An electric furnace comprising: a refractory body provided with a reaction-chamber; a conductive bottom-member, for said chamber, provided with a discharge-opening; a central electrode suspended in the chamber above said bottom-member; electrodes projecting laterally into said chamber; and means for causing a discharge of current between the central electrode and the bottom-member and also a discharge of current horizontally through the laterally-disposed electrodes.

9. An electric furnace comprising: a body, of refractory material, provided with a reaction-chamber and with a discharge-opening; primary electrodes arranged to conduct current through the body of material in the reaction-chamber above the discharge-opening; an electrode operable upon the material at the discharge-opening; an electrode, coöperating with the last-mentioned electrode, and projecting into the material above the discharge-opening; a source of current for energizing the primary electrodes; and an independently controllable source of current for energizing the other said electrodes.

10. An electric furnace comprising: a refractory body provided with a reaction-chamber; an electrode, at the bottom of the chamber, provided with a discharge-opening; electrodes entering the chamber laterally; and a valve-member depending within the chamber and coöperating with the first-mentioned electrode to adjustably restrict the discharge-opening.
